WARP AND HARNESS STOP MOTION FOR LOOMS

Harold H. Babb, Spartanburg, and Dwight L. Moody, Drayton, S. C.

Application September 24, 1945, Serial No. 618,170

3 Claims. (Cl. 139—337)

1

This invention relates to a warp and harness stop-motion for looms, and has for one of its objects the production of a simple and efficient means for automatically tripping the plunger of the flexible cable to stop the loom should the harness become too low and contact the tripping bar.

A further object of this invention is the production of a simple and efficient harness contact means for actuating the flexible cable to stop the loom and thereby prevent an inferior grade of cloth from being made in the event that the harness should become too low.

Other objects and advantages of the present invention will appear throughout the following specification and claims.

In the drawings:

Figure 1 is a fragmentary front elevational view of the harness and tripping mechanism;

Figure 2 is a perspective view of one of the tripping members;

Figure 3 is a transverse sectional view through one of the tripping members, illustrating the manner in which the plunger engages the tripping bar;

Figure 4 is a transverse sectional view through the tripping member illustrating the yieldable supporting means for the tripping bar;

Figure 5 is a longitudinal sectional view of a modified form of the tripping member, certain parts being shown in elevation;

Figure 6 is an enlarged side elevational view of the lower supporting end of the tripping member in an upright position;

Figure 7 is a similar view illustrating the tripping member in an adjusted inclined position.

By referring to the drawings, it will be seen that 10 designates the conventional harness of a loom, the harness being suspended by the conventional suspension means 11. The loom harness 10 is adapted to hang close to the tripping bars 12 of the tripping mechanism A. A separate tripping mechanism A is preferably located near and under each end of the harness 10, as shown. A loom knock-off M of the conventional type controls the operation of the loom in the conventional manner. While the present invention is particularly adapted for use upon the "High speed rayon loom" manufactured by Draper Corporation the present invention may be adapted to other types of looms without departing from the spirit of the invention so long as the adaptation falls within the scope of the appended claims.

Each tripping mechanism is preferably similarly constructed and comprises a tripping bar

2

12 which is yieldably supported by expansion springs 13 which fit around depending guide pins 14. The bar 12 is vertically slidable within a longitudinal channel 15 formed in the bridge portion 16 of the tripping mechanism A. The bridge portion 16 is supported by the depending arms 17, which arms 17 converge toward their lower ends and merge into a supporting lug 18. A journal pin 19 anchors the lug 18 upon a selected location of the loom frame 20 and constitutes a pivotal support by passing through the aperture 21. An adjusting pin 22 by selectively fitting in one of the apertures 23 in the lug 18 and engaging the socket 24 in the frame 20 will hold the tripping member 15 at a selected incline to the horizontal plane of the frame 20 if such a selected inclined position is desired by the operator. The position of the pins 14 may be adjusted by means of a cotter-pin 25 fitting in one of the apertures 26 to regulate the tension of the spring or springs 13 and to adjust the position of the trip bar 12 relative to the harness 10. Each tripping mechanism A is provided with upstanding ends or abutments 12a to prevent the harness 10 from falling to the floor when and if the harness breaks.

An actuating plunger 27 operates a flexible rod tube 28 and this tube 28 connects to loom knock-off M, as at 29. The plunger 27 contacts the under face of the bar 12 and is adapted to cause the loom knock-off to stop the loom should the harness 10 become too low and contact the bar 12. The weight of the harness 10 by contacting the bar 12 will immediately depress the plunger 27 which actuates the flexible tube 28 to cause the loom knock-off to stop the loom. The casing of the plunger 27 may be adjusted to a suitable contacting position for the plunger and held in such a position by means of a clamping screw 30 which is carried by the depending boss 31.

In Figure 5 there is shown a modified form of the invention wherein the tripping mechanism comprising a bridge portion 32 carries a tripping bar 33. This bar 33 is supported by a plurality of springs 34 which are carried by the guide pins 35, similar to the guide pins 14. A plurality of actuating plungers 36 contact the tripping bar 33 and lead to the loom knock-off for stopping the loom. The plungers 36 may be connected in any suitable manner to cause the loom knock-off to stop the loom when either plunger is depressed. Any number of plungers, such as the plungers 36, may be used without departing from the spirit of the invention.

Each loom has a tripping mechanism A placed on one side of the loom, and a second tripping

mechanism similar to mechanism A placed on the opposite side of the loom to take care of the harness.

From the foregoing description it should be understood that by means of the harness-actuated tripping mechanism, the loom will be cut off if the harness should break or become too low whether or not the warp stop-motion is working.

Having described the invention, what is claimed as new is:

1. A stop-motion device for use with a loom having a harness, a support, a stop-motion tripping member located below and in close proximity to the harness, said tripping member comprising a bridge portion and means for anchoring the same to said support, said bridge portion having an elongated channel in its upper face, a tripping bar fitting in said channel, means for yieldably supporting said bar in said channel, a flexible rod tube having a plunger engaging the bar for connection with a loom knock-off to automatically stop the loom when the harness contacts the bar and depresses the bar.

2. A stop-motion device for use with a loom having a harness, a support, a stop-motion tripping member located below and in close proximity to the harness, said tripping member comprising a bridge portion and means for anchoring the same to said support, said bridge portion having an elongated channel in its upper face, a tripping bar fitting in said channel, means for yieldably supporting said bar in said channel, a plu-

rality of flexible rod tubes having plungers engaging said bar for connection with the loom knock-off to automatically stop the loom when the harness contacts the bar and depresses the bar.

5 3. A stop-motion device for use with a loom having a harness, a stop motion tripping member located below and in close proximity to the harness, said member having a tripping bar extending transversely of the harness, said tripping member comprising a bridge portion, yieldable means carried by the bridge portion for yieldably supporting the tripping bar, a flexible rod tube engaging the tripping bar and connected to the operating mechanism of a loom for automatically shutting off the operating mechanism when the harness descends below a predetermined point, and abutments at the ends of the stop-motion tripping member for preventing the harness from falling to the floor when the harness breaks.
